MULTIPLYING MACHINE

William Lang, New York, N. Y., and George B. Heddendorf, New Brunswick, N. J., assignors to International Business Machines Corporation, New York, N. Y., a corporation of New York

Application September 10, 1937, Serial No. 163,300

8 Claims. (Cl. 235—61.8)

This is a continuation in part of application Serial No. 99,370, filed September 4, 1936.

This invention relates to improvements in accounting machines and more particularly, multiplying accounting machines.

The present invention has for one of its objects the provision of an improved type of multiplying machine in which the method of computation technically known as "duplication" is employed.

According to the mathematical principles underlying the invention, a geometrical progression with a ratio of 2 is formed in which the multiplicand factor is the first term of the series. Thus with a multiplicand factor of say 1580 the series would be 1580, 3160, 6320, 12640, 25280, etc. In accordance with the value of the multiplier factor, there is selected from this series the term which equals, or the plurality of terms which when added together equal, the product of the two factors. The procedure is to repeatedly reduce the value of the multiplier as the multiplicand increases. This reduction is termed "halving" so that, if, with a multiplier of 16, the two series are set down as follows:

Multiplicand 1580 3160 6320 12640 25280
Multiplier 16 8 4 2 1

the product 25280 is obtained and is found above the multiplier term whose value is odd. This holds true if all other terms in the multiplier series are even.

Where more than one odd term appears in the multiplier series, the product is the sum of the multiplicand terms above the odd multiplier terms thus:

Multiplicand 1580 3160 6320 12640 25280
Multiplier 18 9 4 2+ 1+

Here the product is $3160 + 25280 = 28440$. It is to be noted that the fractions resulting from "halving" the odd numbers are ignored. Again, for the problem 1580×15 ,

Multiplicand 1580 3160 6320 12640
Multiplier 15 7 3 1

the product is $1580 + 3160 + 6320 + 12640 = 23700$.

It will be observed that in building the parallel series of numbers that the effect has simply been

to restate the problem in terms of different factors, thus:

$$1580 \times 16 = 3160 \times 8 = 6320 \times 4 = 12640 \times 2, \text{ etc.}$$

and

$$1580 \times 18 = 3160 \times 9 = 6320 \times 4 - \frac{1}{2} = (12640 \times 2) + 3160 \text{ etc.}$$

It is to be further observed that where the fraction $\frac{1}{2}$ is involved, such product may again be restated as in the expression:

$$6320 \times 4 - \frac{1}{2} \text{ to read } (6320 \times 4) + 3160.$$

It follows then that the problem of 1580×15 may be restated as follows:

$$1580 \times 15 = (3160 \times 7) + 1580 = (6320 \times 3) + 3160 + 1580 = (12640 \times 1) + 6320 + 3160 + 1580 = 23700$$

From this it is derived that whenever the multiplier term of the series is odd the companion multiplicand term is selected as a term of the product sum.

In constructing a mechanism to carry out the above principles, three accumulators may be employed, one to receive and build up the progressive series of multiplicand terms, a second to receive and build the series of multiplier terms and a third to receive under control of the first two, all the terms of the multiplicand series whose multiplier companion terms are odd. The following table will help to make this clear:

Table I
 $3765 \times 125 = 470625$

"A" accumulator	MC accumulator	#1 accumulator
3765 (odd)	125	125
1882	250	
941 (odd)	500	500
470	1000	
235 (odd)	2000	2000
117 (odd)	4000	4000
58	8000	
29 (odd)	16000	16000
14	32000	
7 (odd)	64000	64000
3 (odd)	128000	128000
1 (odd)	256000	256000
		470625

Thus, in eleven steps, which is the number re-

quired to reduce 3765 to 1, the final product may be obtained and inspection will show that the maximum number of steps for any four place multiplier is thirteen.

5 Where greater rapidity of operation is desired, the number of steps can be considerably reduced by separating the multiplier into two components, as in the following table:

10 *Table II*
 $3765 \times 125 = 470625$

	A	B	MC	#1	#2
15	37 (odd)	65 (odd)	125	125	125
	18	32	250	500	
	9 (odd)	16	500		
	4	8	1000		
	2	4	2000		
	1 (odd)	2	4000	4000	
20			8000		8000
				4625	8125
					4625
					470625

25 Here the multiplier is divided into two parts 37 and 65 and whenever the amount in the A accumulator is odd, the amount in the MC accumulator is entered into the #1 accumulator and whenever the amount in the B accumulator is odd the amount in the MC accumulator is entered into the #2 accumulator. When the multiplier is so reduced to separate two place multipliers, the maximum number of steps involved in reducing the two place number to 1 is six and 35 after the reduction the separate products are combined with a two place column displacement to form the complete product.

A still further reduction in the number of steps is possible if the multiplier is divided into single 40 digits, and a separate accumulator provided for each. The maximum number of steps in such case is three, before the separate sub-products are combined with a single place displacement. This is illustrated below:

45 *Table III*
 $3765 \times 125 = 470625$

	A	B	C	D	MC	#1	#2	#3	#4
50	3	7	6	5	125	125	125		125
	1	3	3	2	250	250	250	250	
		1	1	1	500		500	500	500
55						375	875	750	
								625	
								750	
								875	
								375	
									470625

60 One of the principal objects of the invention is, therefore, the provision of an accumulator, into which an amount may be entered and the amount thereafter automatically "halved" in successive steps.

65 A further object resides in the provision of an accumulator in which means is provided for reading out the complement of half the amount standing therein and reentering said complement to reduce the initial amount by half.

70 A more specific object is to provide a halving readout for an accumulator in which the tens complement of exactly half the amount standing in the accumulator is automatically reentered when the amount is an even number and the nines complement of half the next lower even

number is reentered when the amount is an odd number.

A further object is to provide mechanism for determining whether the amount standing on an accumulator is an odd number to cause said mechanism to control the transfer mechanism between the accumulators. 5

A still further object is to provide mechanism to test an accumulator to determine whether the amount standing on the accumulator is even or odd and to cause the entry of a "1" in the units order of the accumulator if the amount is an even number. 10

Various other objects and advantages of the invention will be obvious from the following particular description of forms of mechanism embodying the invention or from an inspection of the accompanying drawings; and the invention also constitutes certain new and useful features 15 of construction and combination of parts herein- 20 after set forth and claimed.

In the drawings:

Figs. 1, 2, and 3, taken together and arranged vertically in the order named, show the wiring 25 diagram of the electric circuits of the machine.

Fig. 4 is a view showing the driving mechanism for feeding the record cards.

Fig. 5 is a view showing the card advancing and analyzing mechanism.

Fig. 6 is a view showing the accumulator resetting mechanism.

Fig. 7 is an isometric view showing one order of the accumulator mechanism.

Fig. 8 is a timing chart showing the timing of 35 the electrical devices of the machine.

Fig. 9 is a sectional view of the printing mechanism.

Fig. 10 is a view of a controlling record card in which multiplicand and multiplier factors are 40 perforated.

Fig. 11 is a view showing the manner in which a typical computation is performed by the machine.

Fig. 12 is a detail of a special readout device.

Fig. 13 is a detail of mechanism for entering an 45 "elusive one" into an accumulator.

Before describing the construction of the machine to which the present invention is shown applied, the general principles under which the machine operates and the general mode of operation will be set forth in connection with a selected problem. 50

Referring to Fig. 11, there are represented diagrammatically the steps involved in solution of the problem 596329×1580 . The record card bearing the two factors to be multiplied is first advanced to pass the analyzing brushes where the multiplicand factor 1580 is read and entered into the accumulator designated MC. The multiplier factor 596329 is read concurrently with the multiplicand and entered into the multiplier accumulators A, B, and C, as three separate smaller multipliers and the machine effects multiplication separately for each part. Thus, the multiplicand will be multiplied by 29 in the C section; by 63, in the B section; and by 59, in the A section. 55

After the card has been sensed, the accumulators will contain the amounts indicated after the 70 line entitled "Enter MP and MC." In the following computing cycles, it is the object to cause the repeated doubling of the multiplicand amount and the repeated reduction of the amounts in the A, B, and C accumulators by an 75

amount equal to the whole part of half the initial amounts. This is effected in the present machine by subtracting from each of the A, B, or C accumulators an amount equal to half the entry, if such entry is an even number, or, if the number is odd, half of the next lower even number. For convenience in construction, this subtraction is effected by complementary addition.

The increasing of the initial multiplicand amount in the MC accumulator is brought about by what will hereinafter be termed "doubling" operations. The doubling operation is represented in Fig. 11 by the curved arrows pointed downwardly to the next line, indicating that the amount in the accumulator is added to itself, or doubled. The reduction of the amounts in the A, B, and C accumulators will hereinafter be termed "halving" operations and are indicated in the same manner as the doubling operation by curved arrows pointing downwardly. Transferring operations are indicated by arrows extending from the amount in the MC accumulator to one of the other three accumulators #1, #2, or #3, indicating that the amount standing in the MC accumulator has been added to such other accumulator.

As mentioned, the machine will perform three separate multiplying operations concurrently with the three sections of the multiplier and will obtain three separate sub-products which will later be combined to form the complete, or final, product. Thus, in following through the problem of Fig. 11, it will suffice to explain, for example, the manner in which the product 29×1580 is obtained. During the second cycle, the amount 1580 in the MC accumulator is read out and re-entered therein. The amount 29 will control the reading out of an amount 85 in the C accumulator. This 85 is the nines complement of 14 which is half of 28, the next lower even number. The accumulator C is provided with two denominational orders only, so that the carry from the tens order is discarded. Before the doubling and halving cycle takes place, the units order of the C accumulator is tested to determine whether the value in that order is an odd or an even number. If it is found to be an odd number, connections are established so that the amount in the MC accumulator will be transferred to ACC#3 currently with the re-entry of the amount into the MC accumulator. Thus, since 29 is an odd number, the multiplicand will be transferred during the second cycle to ACC#3 as well as to the MC accumulator at the same time that the amount in the C accumulator is reduced. After this second cycle, the C accumulator will contain 14; the MC accumulator, the amount 3160; and ACC#3, the amount 1580. During the third, transfer cycle, the operations are repeated; that is, the amount 3160 will be re-entered in the MC accumulator and the amount 93 will be entered in the C accumulator, this being the tens complement of half 14 which is 7. Since the amount 14 is even, there is no transfer operation between the MC accumulator and ACC#3. It is also to be noted that when the amount in the C accumulator is even, the amount re-entered therein is the tens complement of half that amount, while when the amount standing therein is odd, the amount entered is the nines complement of half the next lower even number. After the third cycle, the amount standing in the C accumulator is 7; MC contains 6320, and ACC#3 contains 1580. In the fourth cycle, which now follows, the MC amount is again doubled and since the amount in C is

odd, the amount in MC is also transferred to ACC#3 and the nines complement of 3, which is 96 is entered into accumulator C to reduce the amount therein to 3. The fifth cycle and the sixth cycle are repetitions of the fourth cycle as the amount in the C accumulator is odd and will cause the transfer to the #3 accumulator during both cycles while the MC accumulator continues doubling. At the end of the sixth cycle the amount in the C accumulator is zero and no further effective change will take place in this accumulator and no transferring will take place during the seventh cycle so that at the end of the seventh cycle, the amount standing in ACC#3 will be 45820, which is the product of 29×1580 . During the seventh cycle the nines complement 99 is added into accumulator C together with a fugitive 1 digit with the net result of returning the accumulator setting to zero. The machine thus "halves" zero in this cycle and again in the eighth cycle.

During these transferring cycles, similar operations have taken place to cause the repeated reduction of the amount in the B accumulator and the transfer of the amount in the MC accumulator to ACC#2 whenever the units order of the B amount represented an odd number, and similarly, the amount in the A accumulator controls the transfer from the MC accumulator to ACC#1 so that after the seventh cycle, ACC#1 will contain the product of 59 times the multiplicand and ACC#2 will contain 63 times the multiplicand.

The maximum number of halving cycles to effect a reduction of any two-place multiplier to zero is seven and the machine has accordingly been arranged to invariably perform seven halving cycles. If the number entered in either A, B, or C is a small number so that it reaches zero in less than seven cycles, the remainder will merely be idle cycles. Thus, the number 29 is reduced to zero in five cycles and the last two effected no effective change in the status of the associated accumulators. It will be apparent that if the machine were constructed to handle only multipliers of three denominations, a single digit would be entered in each of the A, B and C accumulators and the number of halving cycles reduced to four which is the maximum number necessary to reduce any single digit to zero.

After the three sub-products have been obtained, the machine performs two so-called "gathering" cycles during the first of which the amount in ACC#2 is transferred to ACC#3 with the transferred amount offset two decimal places to provide the proper denominational allocation. During the second gathering cycle, the amount in ACC#1 is similarly transferred, with the number offset four decimal places so that after the ninth cycle, ACC#3 contains the final product 942199820. There now follows the final cycle during which the product is printed and the machine is reset in preparation for the next problem.

The accounting machine to which the present invention is shown as applied, so far as the mechanical construction is concerned, is similar to the machine shown and described in U. S. Patent No. 1,976,617, granted October 9, 1934 to C. D. Lake and G. F. Daly, to which reference may be had for a fuller description of the general operation of the various units and the manner of drive. There are certain differences in the present construction over the machine shown in the above mentioned patent which will be pointed out hereinafter.

In the following, the separate units of the machine will first be described to explain their manner of operation, after which the circuit diagram will be described to point out the manner in which the several units are coordinated.

Card feeding mechanism

The card feeding mechanism shown in Figs. 4 and 5 is similar to that shown and described in the patent referred to, except that provision is made in the form of a clutching device for interrupting the card picker operations without stopping the accumulating drive mechanism. In Fig. 4, 10 represents the drive shaft of the machine which may be directly connected or detachably coupled to a suitable driving motor.

In Fig. 5, the analyzing brushes are indicated at UB and the record cards R are successively advanced by picker 11 to a first pair of feed rollers 12 which serve to advance the cards to further pairs of feed rollers 13 which advance the cards to pass the brushes UB. The shafts upon which rollers 13 are mounted are provided with gears 14 at their extremities and arranged as shown in Fig. 4 to be driven through gearing 15 from gear 16 on the drive shaft 10. It is thus seen that the rollers 13 are in constant rotation. From one of the gears 15 a gear 17 is driven through an idler 18, which gear 17 is freely mounted upon a shaft 19. Secured on shaft 19 is a gear 20 which serves to drive the picker mechanism and the first pair of feed rollers 12. Also secured on shaft 19 is a clutch arm 21 carrying a spring-pressed dog 22, which dog and arm are normally latched in the position shown by latching armature 23 pivoted at 24 and controlled by a magnet 25.

Energization of magnet 25 will release dog 22 for engagement with driving element 26 which is secured to the constantly running gear 17 so that gear 20 will be driven for one revolution during which the picker 11 will advance the record card from the magazine to rollers 12 which feed it to the dotted line position indicated in Fig. 5, where the leading edge of the card is beneath the brushes UB.

At the brush station, there is provided a pair of card lever contacts designated UCL, which are operated by the usual card levers to close as the record card passes the station and to remain open unless a card is present. During the doubling, halving, transferring, gathering, and product printing cycles, magnet 25 is deenergized and card feeding will, of course, not take place during such cycles.

55

Accumulating mechanism

The adding mechanism is entirely similar to that shown and described in the patent referred to and the description thereof will accordingly be limited to a brief explanation of its manner of operation. The drive shaft 27 (Fig. 7) is directly geared to the main shaft 10 in Fig. 4 so that it is in operation as long as the driving motor of the machine functions and the driving ratio is such that shaft 27 makes one revolution for each card feeding cycle of the machine. The shaft 27 has slidably mounted thereon but keyed for rotation therewith a clutch element 28, one for each denominational order of the accumulator. The element 28 is provided with a groove into which fits the end of the short arm of a lever 29 which is pivoted as shown and provided with a block 30 normally held as in Fig. 7 by armature latch 31 of adding magnet 32.

A leaf spring 33 bears against the extremity of the longer arm of lever 29 and moves the same in a counter-clockwise direction upon release of block 30 by armature 31. This movement will bring clutching member 38 into engagement with cooperating teeth 34 integral with a gear 35 loosely mounted on shaft 27. Gear 35, when thus coupled to shaft 27, will rotate a gear 36 which meshes therewith and will displace the accumulator index wheel 37. The rearward extremity 10 of member 29 is adapted to be engaged by a finger 38 toward the end of the cycle for the purpose of disengaging clutching element 28 from teeth 34 and re-latching block 30 on armature 31.

Briefly summarizing the adding operation, the magnet 32 may be energized at various points in the cycle of the machine depending upon the location of a perforation in a column of the card analyzed by the brushes UB. This energization may take place in response to a perforation in any of the index point positions from 9 to 1, inclusive. A perforation in the 9 index point position will trip the clutch element 28, nine steps before finger 38 is operated to declutch it and a perforation in the 1 index point position will trip the clutch element 28 one step before it is declutched by the finger 38. Each step of clutching engagement corresponds to a tenth of a revolution of the accumulator index wheel 37 so that a 9 hole will cause it to move nine-tenths of a revolution and the 1 hole will cause it to move one-tenth of a revolution. The manner in which circuits through the brushes UB control the operation of magnet 32 will be set forth in connection with the explanation of the circuit diagram. Suitable carry mechanism between the several orders of the accumulator mechanism are provided and these are exactly similar to that shown in the Patent No. 1,976,617 so that illustration thereof is omitted.

40

MC readout mechanism

Also driven by gear 35 (Fig. 7) is a gear 39. Since the ratio of gears 39 and 35 is 2:1, the former will turn through a half revolution for each revolution of the latter. Carried by and insulated from gear 39 is a pair of electrically connected brushes 40, one of which cooperates successively with ten conducting segments 41, while the other cooperates with an arcuate conducting strip 42.

The relationship of the parts is such that when the index wheel 37 is in its zero position, one of the brushes 40 in contact with the zero segment 41 and the other brush is in contact with the strip 42, thus forming an electrical connection between the two. If the wheel 37 is displaced to indicate, say 8, then one of the brushes 40 will be in contact with the 8 segment 41 and the other brush will be in contact with the arcuate strip 42. The positioning of the brushes 40 provides a convenient electrical readout mechanism for controlling doubling, transferring, gathering, and product printing operations, and the electrical circuits involved in these functions will be more fully explained in connection with the circuit diagram.

55

60

65

Printing mechanism

The printing mechanism is shown in Fig. 9 where the usual so-called listing shaft 43 carries 70 a clutch driving element 44. The shaft 43 has direct driving connection with the constantly running shaft 10 (Fig. 4) so that clutch driving element 44 may rotate continuously. The listing cam 45 is freely carried on the shaft 43 and 75

75

provided with a spring-pressed clutching dog 46 adapted for engagement with the driving element 44. Dog 46 is normally held out of engagement by arm 47 controlled by magnet 48.

5 Energization of magnet 48 will permit cam 45 to rotate with the listing shaft 43 and follower arm 49 will cause oscillation of rocker shaft 50 to which are secured arms 51 link-connected to the reciprocating crosshead 52 so that for each 10 revolution of cam 45, crosshead 52 will be moved upwardly and then down again to its initial position. Slidingly mounted in the crosshead are type bars 53 spring urged into movement with the crosshead as it rises. As type bar 53 moves 15 upwardly, ratchet teeth 54 successively pass the nose of stopping pawl 55 as the type elements 56 successively pass printing position opposite platen 57.

Energization of printing magnet 58 as the type 20 bar moves upwardly will draw call wire 59 toward the right to rock the latch 60 out of engagement with stopping pawl 55 whereby the nose of the latter will engage one of the teeth 54 and interrupt further upward movement of 25 the type bar. Before the crosshead 52 moves downwardly, the usual printing hammers are tripped to take an impression from the selected type elements.

Accumulator resetting mechanism

30 The shaft 61 (Fig. 6) upon which the index wheels 37 of an accumulator are loosely mounted is slotted for cooperation with the usual spring-pressed pawls (Fig. 12) pivoted upon and carried by the individual index wheels in such manner that counterclockwise rotation of shaft 61 will engage and drive the index wheels 37 forwardly to zero position during a single revolution of shaft 61.

Referring to Fig. 6, shaft 61 carries a gear 62 40 at its extremity which is in engagement with gear 63 mounted upon reset shaft 64. Gear 63, of which there is one for each accumulator, may be selectively coupled to the resetting shaft 64 in the well known manner more fully explained in 45 the patent above referred to. At the extremity of shaft 64 is a gear 65 which is adapted to be driven by an intermittent gear 66 which is secured to shaft 67. Also fixed to shaft 67 is an arm 68 which carries spring-pressed clutch dog 69 normally held in the position shown in Fig. 6 50 by a latching arm 70 supported by armature shaft 71 of magnet armature 72. Energization of magnet 73 will release dog 69 for engagement with clutch driving element 74. Element 74 is integral with a gear 75 which meshes with a gear 76 secured upon constantly running shaft 43.

With this arrangement, driving element 74 is 60 in constant rotation and whenever it is desired to effect resetting of the accumulators, magnet 73 is energized to provide a connection between the element 74 and the resetting shaft 64 to cause concurrent resetting of all the accumulators.

MP readout mechanism

65 The readout mechanism for the multiplier accumulators A, B, and C is shown in Fig. 12. As explained, each of these accumulators contains two denominational orders and entries are effected into the numeral wheels 37 in exactly the same manner as into the wheels of the MC accumulator described above. These accumulators are also provided with a readout for each order, but differ from the MC readout in that 70 instead of having ten separate contact segments

75 there are provided only four, indicated at 41a, which represent pairs of numbers as indicated. In addition, the gear 39 which positions the readout brushes 40 drives a further gear 39a through an idler 39b and will cause rotation of a second pair of sensing brushes 40a. These brushes cooperate with contact segments 41b which are provided only in the odd number positions so that when the brushes 40a stand at an odd number, there is an electrical connection 10 between one of the segments 41b and a common strip 42b.

The units order of each of the accumulators A, B, and C is provided with means for effecting a so-called "elusive" one entry. This mechanism is shown in Fig. 13 wherein the units position is provided with the usual carry pawl arm 108 normally held in the position shown, by a latch 109. Energization of carry magnet 110 will release pawl 108, permitting the same to rock 20 clockwise upon shaft 61 so that pawl 111 carried thereby will move into engagement with the next tooth on ratchet 112 which is integral with the adding wheel 37. The usual carry bail 113 will thereafter engage lever 108 to restore it to the 25 position of Fig. 13 and during such restoring movement the pawl 111 will advance the ratchet 112 and wheel 37 one place. In Fig. 8 there is indicated by the legend "Carry period" the time in the cycle of operations when bail 113 moves 30 lever 108 to advance the wheel one step.

General explanation of the circuit diagram

The wiring diagram of the electric circuits of the machine is shown in Figs. 1, 2, and 3, wherein 35 the various cam controlled contact devices are diagrammatically shown and suitably labelled L, CR, or TP for identification. The cams prefixed L operate only during the card feed cycle. The cams prefixed TP operate only during the total 40 print and reset cycle, while those prefixed CR and the emitters prefixed E are in constant operation. The timing of these contact devices is shown in the timing diagram (Fig. 8) to which reference may be made for the time in the cycle 45 of operations during which they function.

In this figure the dark lines represent the period during which the cam contacts are closed. Due to the numerous circuit connections involved in the present arrangement, it has not been advisable in all instances to show the relay magnets and their associated contacts in close proximity to one another. For purposes of clarity in the wiring arrangement, the relay contact points are shown in the circuits which they control and their relay magnets are dotted adjacent thereto. Further, the different contacts are designated with the same reference character as the controlling magnet, followed by a numeral. The complete circuit diagram will now be described in detail and the various operations will be set forth in the order of their occurrence.

For each record card there will be eleven cycles. Of these cycles there will be for each card first, one cycle during which the card is moved to pass 65 the brushes UB. Following this, there will be seven doubling, halving, and transferring cycles, after which will follow two so-called gathering cycles, and then the product printing and resetting cycle, thus making eleven cycles for each 70 computation.

Starting cycles.—Referring to Fig. 1, the switch 71 is first closed to connect the motor M between the main lines 80 and 50. With the motor M in operation, the several constantly rotating 75

shafts and the CR cams commence rotation. Depression of the start key to close contacts 78 will cause energization of the card feed clutch magnet 25 and the card picker mechanism will 5 operate to feed the first card from the magazine to the first pair of rollers 12.

At the end of this cycle, the card will be at the dotted line position shown in Fig. 5. A second depression of the start key 78 will again energize 10 magnet 25 and the first card R will advance to pass the brushes UB while the second card is advanced by the picker 11.

As the brushes UB traverse the multiplier and multiplicand fields of the card, circuits will be 15 completed through the perforations representing the factors. It may be here explained that in the circuit diagram, sufficient mechanism has been shown to handle a six place multiplier and a more limited number of places for the multiplicand. This has been done to obviate the repetition of similar parts.

Entering circuits.—The manner in which the amounts are entered into the accumulators will now be explained and the control circuits traced. 25 As the card continues downwardly to pass the brushes UB, the multiplicand amount is entered into the accumulator MC. The entering circuits are traceable (Fig. 3) from line 90, through cam contacts CRI, card lever contacts UCL, brush 30 UB, and through plug connection 91 to contacts H2 (closed as will be explained) and adding magnet 32 of accumulator MC. Similarly, circuits are completed (Fig. 1) through connections 92 to the adding magnets 32 of the multiplier accumulators A, B, and C through relay contacts H3. The contacts H2 and H3 are provided to prevent undesirable back circuits and are controlled by relay magnet H, shown in Fig. 1. The operation is as follows:

40 As the card moves to pass the brushes, the relay magnet H is energized and contacts H2 and H3 are closed. The cam contacts L4 close to energize the relay H if a card is advanced to close card lever contacts UCL, thereby closing its contacts H1. The contacts L4 maintain magnet H energized through that portion of the cycle during which the card traverses the brushes so that at such time the contacts H2 and H3 are closed and they are open at all other times.

50 The energization of relay magnet H will close its contacts H1 thereby completing the circuit through relay magnet F extending from line 80, through contacts H1, relay F, and cam contacts TP3 which are normally closed. Magnet F will 55 close its contacts F2 which establish a holding circuit through relay magnet F which will accordingly remain energized until contacts TP3 open near the end of the resetting cycle of operations.

60 *Doubling circuits.*—When an amount is to be read out of the MC accumulator and re-entered therein to effect doubling of the amount, a plug connection 95 (Fig. 3) is made between the plug socket 96 of that accumulator and relay contacts D1, and a further plug connection 97 is made from the contacts D1 to socket 93 of the same accumulator.

Due to the closure of contacts D1, a circuit 70 is traceable as follows: from line 90, wire 98, emitter E2, through wires 99, readout segments 41, brushes 40, common strip 42, socket 96, connection 95, contacts D1, connection 97, socket 93, adding magnet 32, to line 80. The adding magnet 75 net 32 of the accumulator will thus be energized

at the time determined by the position of the readout brush 42 in the related order.

Transferring circuits.—When it is desired to transfer an amount from the MC accumulator to any of the others, the connection 100 is made 5 from the readout socket 96 to the contacts 1T2, 2T2 and 3T2 and further connection 101 is made to extend toward the adding magnet 32. Thus, with contacts 1T2 closed, for example, a circuit will extend from line 90, wire 98, emitter E2, 10 wires 99, segments 41, brushes 40, readout strip 42, socket 96, connection 100, contacts 1T2, connections 101 to socket 93, and thence through magnet 32 to line 80. The magnet 32 of ACC#1 will thus be energized in accordance with the 15 amount standing on accumulator MC.

Gathering circuits.—When it is desired to gather the sub-products from ACC#1 and ACC#2 into ACC#3, a plug connection 102 is made to contacts 1G2 and a connection 103 is made to 20 contacts 2G2. Further connections 104 and 105 are made from these contacts to sockets 93 of ACC#3 in the proper denominational positions. When contacts 1G2 are closed, the gathering circuit which is similar to the above described transferring circuit will follow from the common strip 42 in the units order of ACC#1 through connection 102, contacts 1G2, connection 104, socket 93 of the tens of thousands order of ACC#3 and thence through magnet 32 in that order to line 80. 30

If contacts 2G2 are closed, a similar circuit is traceable from the readout strip 42 in the units order of ACC#2 through connection 103, contacts 2G2, connection 105 to the socket 93 in the hundreds order of ACC#3 and thence through the 35 adding magnet 32 of that order.

Product printing circuits.—When the final product is to be printed, contacts P5 are closed and through plug connections 106 and 107 made thereto, circuits may be traced from the readout 40 strip 42 in the units order of ACC#3, through connection 106, contacts P5, connection 107, printing magnet 58, to line 80.

The above describes briefly the manner in which the different doubling, transferring, and 45 product printing circuits are completed and in Fig. 3 has been shown the plug connections for a single order of each of the accumulators. It will be understood that similar connections are made in the other positions.

Halving circuits.—The manner in which an entry is read out of accumulators A, B, or C and re-entered therein to control the entry of a complement will now be explained. In the description, specific reference will be made to accumulator A and it will be understood that the operation of the B and C accumulators is the same. The amount standing in the tens order of the A accumulator is read out as the nines complement of half the number standing therein, if the number is even, or half the next lower even number, if the number is odd. The circuits may best be understood by tracing a specific example. Assuming the brush 40 in the tens order of the A accumulator to be standing at 8, a circuit is 60 traceable during any transfer cycle while the emitter E1 is rotating, which follows from right side of line 90 through the "5" spot of emitter E1 to the "5" wire 115, wire 116, to the 8, 9 segment 41a, brush 40, common conductor 42, to 65 plug socket 117 and thence through plug connection 118 to contacts D2 which are closed during doubling operations, as will be explained, plug connection 119 to the adding magnet 32 of the tens order. This impulse, being at the "5" time 75

in the cycle, will cause the entry of a "5" into the order, which is the nines complement of half of 8. In the same manner, if the brush 40 were standing at 9, a "5" would also be entered. Thus, for the problem in Fig. 11, with the initial entry of 59 in the A accumulator, the "5" standing in the tens order of this accumulator will cause the entry of a "7" into the same order.

The segments 41a of the units order are connected through wires 120 to the same wires 115 to which the corresponding segments 41a of the tens order are connected. Inserted in the wires 120 are contacts K1 which are normally closed and if, during a transfer cycle, contacts K1 remain closed, the amount read out of the units order and re-entered therein will be effected in the same manner as explained for the tens order. Thus, if the brush 40 of the units order is standing at 8, the circuit is traceable from line 90, through emitter E1, the "5" wire 115, the wire 120 farthest to the right, contacts K1 "8", "9" segment 41a, brush 40, common strip 42, plug socket 117, connection 118, contacts D2, and magnet 32 of the units order.

If the tens digit standing on the accumulator is odd, the contacts K1 are open and contacts K2 closed, thus connecting the units segments 41a to wires 115 through a group of wires 121. The "8, 9" segment 41a of the units order is entirely disconnected when contacts K1 open as no contact K2 is provided in this position. The wires 121 connect the units order segments 41a to wires 115 representing the complement of the amount standing in that order plus 5, if the tens order digit is even. If the tens order digit is odd, it will be the complement of half the next lower even number plus 5. For example, with the brush 40 of the units order standing in, let us say, the "6" position, with contacts K2 closed, the circuit is traceable from line 80, unit adding magnet 32, contacts D2, connection 118, socket 117, conductor 42, brush 40, "6, 7" segment 41a in the units order, contacts K2, wire 121 to the "1" wire 115, emitter E1, to line 90. Thus, with the units brush standing on "6" or "7", a circuit is completed to add "1" into the accumulator when the tens order is an odd number.

The contacts K1, K2 are shifted by the relay magnet K which is energized when the tens order contains an odd digit. For this purpose, the readout contact segments 41b and common strip 42b are utilized and as the brush 40a, cooperating with these segments, takes a position on one of them, a circuit is completed from right side of line 90, through cam contacts CR4, which close after an entry has been made, relay contacts F3, which close during the card feed cycle and remain closed until the total printing cycle, conductor 42b, brush 40a, odd number segment 41b, a relay magnet M, relay K, and wire 122, to line 80. Magnet M closes its contacts M1, setting up a holding circuit from line 90, cam contacts CR2, contacts M1, relays M, K, and wire 122, to line 80. The relay magnet K is energized, if the digit in the tens order is odd, at the end of the card feed cycle after an entry has been made and is held energized throughout the entering portion of the next following cycle, during which time the halving, doubling, and transferring operations take place.

After entries have been made, contacts CR2 open and later in the cycle contacts CR4 again close to sense the new amount standing on the accumulator and if the tens order thereof is still odd, relay magnet K will again be energized, and

if the number is even, the circuit will not be completed and contacts K1 will remain closed.

The readout segments 41b in the units order of accumulator A control the operation of relay magnet IT which controls the contacts IT2 of Fig. 3, which, as explained, complete the transfer circuits from the MC accumulator to ACC#1. As was explained, this transfer takes place whenever the digit in the units order of accumulator A is odd. A circuit is completed whenever the brush 40a stands on one of the odd segments 41b. This circuit is traceable from line 90, contacts CR4, F3, wire 123, units order segments 41b, brush 40a, common conductor 42b, relay magnet N, magnet IT, wire 122, to line 80. It is completed concurrently with that which energized the magnet K. Relay N closes its contacts N1, setting up a holding circuit through contacts CR2 which hold the circuit energized through the entry portion of the next following cycle. Thus, if both the units and tens digits are odd, magnets K and IT are concurrently energized and held so, for the same period.

In the carrying out of the problem, it is necessary whenever the units digit is even to enter an extra one into that order to, in effect, enter the tens complement of half the value of the digit. For this purpose, relay N is provided with a normally closed pair of contacts N2 and if the amount standing in the units order is even, magnet N, as we have seen, will remain deenergized. Near the end of each cycle, cam contacts CR3 close after contacts CR4 have closed and a circuit will be completed from line 90, through cam contacts CR3, contacts N2, contacts D5, relay magnet R, the "elusive" one magnet 110, to line 80. Relay magnet R closes its contacts R1 to provide a holding circuit through cam contacts CR7 which maintain the circuit over into the next cycle to insure the proper operation of the mechanism controlled by magnet 110 to enter a "1" by means of the carry mechanism of the units order. If the number standing in the units order is odd, the closure of contacts CR4 to energize relay magnet N will have taken place and caused opening of contacts N2 before cam contacts CR3 close so that where the number is odd, the carry magnet 110 is not operated.

The multiplier accumulator circuits have been explained in connection with accumulator A. The accumulators B and C are exactly the same so that they need not be separately described and the contacts CR2, CR3, CR4, and F3 have been shown as a separate set of contacts for each accumulator. But, it is obvious that a single set will suffice for all.

Sequence controlling circuits.—It remains now to explain the mechanism for causing the cycles required for each computation to follow in the proper sequence. In Fig. 1, there is shown diagrammatically a well known type of circuit closing device comprising a common conductor 130 and individual contact segments 131 which are traversed in succession by a brush 132 which is carried by an arm 133 connected to a ratchet 134 and biased in a clockwise direction by a spring 135. Energization of magnet 136 will operate armature and pawl device 137 to advance the brush 132 to the next segment. A spring-pressed holding pawl 138 will retain the brush in its advanced position and upon energization of the release magnet 139, the pawl 138 is withdrawn so that spring 135 may return the brush to home position. During the first cycle, while the factors are being entered into the accumulators, the

brush 132 occupies the position shown in Fig. 1. As we have seen, relay magnet F is energized during this cycle causing closure of its contacts F1 so that near the end of the entering cycle, upon 5 closure of cam contacts CR5, a circuit is completed from line 80, contacts F1, CR5, magnet 136, to line 90. This will cause advance of the brush 132 to connect the "2" segment 131 to the conductor 130 whereupon a circuit is traceable from 10 line 80, through wire 140, conductor 130, brush 132, "2" segment 131, relay magnet D, cam contacts CR6 to line 90. Contacts CR6 are closed throughout the entering portion of the next cycle so that, during that period, relay magnet D re- 15 mains energized and will hold its contacts D1 of Fig. 3 and contacts D2 and D5 of Figs. 1 and 2 closed, thus permitting entries to be transferred from the readout devices of the MC, A, B, and C accumulators to the adding magnets of the same 20 accumulators. Near the end of this cycle, magnet 136 is again energized, moving the brush to the third segment 131 and magnet D is again energized. The eighth cycle is provided to take care of the largest possible numbers which require a 25 transfer to be carried out in this cycle. These numbers are 64 to 99 inclusive, each of which requires seven halving operations to reduce it to zero.

The segments "2" to "8", inclusive, are electrically connected to one another so that for each of these cycles magnet D is energized. Near the end of the eighth cycle, the brush 132 is advanced to the "9" segment 131 and when CR6 thereafter closes, relay 1G will be energized to 30 close its contacts 1G2 in Fig. 3 so that the amount standing in ACC#1 may be transferred to ACC#3. Further advance of brush 132 will connect the magnet 2G for energization and this magnet will close its contacts 2G2 of Fig. 3, connecting 35 ACC#2 to ACC#3. Following this, further advance of brush 132 will complete the circuit through magnet P, closing its contacts P5 of Fig. 3 so that the readout device of ACC#3 is connected to the printing magnets 50. Magnet P also closes its contacts P1, shown at the top of Fig. 1, to energize the print clutch magnet 48 so that the printing mechanism will operate during the next cycle and the amount standing in 40 ACC#3 will be printed. If switch 141 is closed, the reset clutch magnet 73 will also be energized to effect resetting of all the accumulators after the product has been printed. During the printing operation, the cam contacts prefixed TP operate, of which contacts TP2 close to energize 45 the resetting magnet 139 of the step-by-step relay. Contacts TP3 open to deenergize the relay magnet F and contacts TP1 close near the end of the cycle to energize the card feed clutch magnet 25 to automatically feed the next following 50 card to pass the brushes UB and from this point on the sequence of operations is repeated for the next computation in accordance with the factors punched on the following record card.

A brief explanation will now be given with 65 reference to the operation of the several relays to more clearly explain their action and timing. Let us assume that a card having the multiplier of 99 and multiplicand of 1580 has been placed in the hopper and that switch 77 is closed.

70 *Card feed cycles.*—As has been explained when first starting the machine, two successive card feed cycles take place and near the end of the first cycle the card engages the card lever to shift the UCL contacts. With these contacts 75 shifted, the multiplier and multiplicand amounts

will be entered in their selected accumulator orders with 99 entered in accumulator A, for example. Relay H is energized throughout the entering portion of the second feed cycle and relay F is also energized, the latter being held until 5 the print and reset cycle when contacts TP3 open. During these two cycles the stepping arm 133 of Fig. 1 remains in the position shown and near the end of the second cycle when contacts CR5 close, arm 133 will be shifted to its "2" position, causing energization of relay D shortly after contacts CR5 close and contacts CR6 will keep this relay energized until after the entering portion of the next cycle. Just prior to the energization of relay D, contacts CR4 test the setting of the 10 tens and units positions of accumulator A and since these both contain a "9", an odd number, relays M, K, N, and 1T are energized and will be held by contacts CR2 coextensively with relay D. Nearer the end of the cycle contacts CR3 close in- 15 effectively as contacts N2 will now be open.

First transfer cycle (2).—At the commencement of this cycle relays D, F, K and 1T are energized so that as emitter E2 operates the MC amount will be read out of accumulator MC and 20 reentered therein and also entered in accumulator #1. Emitter E1 will cause the amount 50 to be entered into accumulator A to reduce the original entry of 99 to 49. When CR4 subsequently closes relay K will not be energized as the 30 tens order of accumulator A is now even, but relay 1T will be energized as the units order is odd. Stepping arm 133 is shifted to position 3 and relay D is again energized.

Second transfer cycle (3).—At the commencement of this cycle relays D, F and 1T are energized and emitter 2 again causes doubling and transferring operations to take place, while emitter 1 causes the amount 75 to be entered into 35 accumulator A to effect a result of 24 therein. 40 Both digits are now even and when CR4 closes, neither K nor 1T is energized. CR5 causes a further shift of arm 133 to its 4 position and relay D becomes energized so that its contacts D5 are closed when contacts CR3 close at the end of the 45 cycle to enable energization of carry magnet 110 to trip the carry lever in the units order of accumulator A. It should be pointed out at this time that while the carry magnet 110 is energized at the end of a cycle the actual entry of the unit 50 does not take place, due to the mechanical structure, until the carry period in the next cycle which is completed before contacts CR4 close in such next cycle.

Third transfer cycle (4).—At the commencement of this cycle relays D, F and 110 are energized. Doubling takes place but no transfer from accumulator MC to accumulator 1. Emitter 1 causes the amount 87 to be added to the amount 24 in accumulator A and during the carry period 60 1 is added to give a result of 12. This amount 65 is again tested by contacts CR4 resulting in the energization of relay K and when CR3 closes, magnet 110 is also energized and the carry lever tripped. Also, stepping arm 133 is shifted to its 5 70 position.

Fourth transfer cycle.—At the commencement of this cycle the relays D, F and K and magnet 110 are energized. Doubling takes place without accompanying transfer to accumulator 1 and 70 emitter 1 causes the amount 93 to be added to the remaining 12 and a unit is entered by the carry mechanism to give a result of 06 in accumulator A. Again, when contacts CR4 close to test the accumulator, both orders are in even condi- 75

tion so that neither K nor 1T are energized and later carry magnet 110 is again energized while the stepping arm 133 is shifted to position 6, to cause relay D to be energized while contacts CR3 are still closed.

Fifth transfer cycle (6).—At the commencement of this cycle relays D and F and magnet 110 are energized. Doubling takes place without accompanying transfer to accumulator 1 and 10 emitter 1 causes the amount 96 to be added to the amount 06 and a further 1 is also entered by the carry mechanism resulting in the amount 03. Again, CR4 tests and causes relays 1T and N to be energized, thus preventing a carry magnet impulse when contacts CR3 close. Again, lever 133 is stepped to its 7 position.

Sixth transfer cycle (7).—At the commencement of this cycle relays D, F and 1T are energized so that accumulator MC transfers to itself 20 and to accumulator 1. Emitter 1 causes the amount 98 to be entered in accumulator A resulting in the reading 01. At the testing time after the shift of lever 133 to its 8 position, relays 1T and N are again energized.

Seventh transfer cycle (8).—At the commencement of this cycle relays D, F, and 1T are energized resulting in doubling in MC and transfer to accumulator 1 while emitter 1 enters 99 into accumulator A to obtain the reading 00. When 30 contacts CR5 now close, lever 133 is shifted to position 9, relay D is not energized, and since its contacts D5 are therefore open when contacts CR3 close, the carry magnet 110 is not energized. In position 9, the lever 133 causes energization of 35 relay 1G.

First gathering cycle (9).—At the commencement of this cycle relays D and 1T are deenergized so that no doubling and no transferring to accumulator 1 can take place, and no entry can 40 be made into accumulator A either by emitter 1 or the carry mechanism so that the setting of 00 in accumulator A remains undisturbed. Emitter 2 causes the amount in accumulator 1 to be entered into accumulator 3. Later, lever 133 is 45 stepped to its 10 position where relay 2G is energized.

Second gathering cycle (10).—This cycle is the same as the preceding cycle except that relay 2G is energized instead of 1G so that the transfer 50 is from accumulator 2 to accumulator 3. For the example under consideration, there is no significant amount in accumulator 2 so that this is in reality an idle cycle. Near its end, arm 133 is stepped to its 11 position energizing relay P.

Print and reset cycle (11).—During this cycle, the print and reset clutch magnets 48 and 73 are energized and the amount in accumulator 3 is printed. Near the end of the cycle contacts TP2 close to effect restoration of lever 133 to its 1 position and contacts TP3 open to deenergize relay F and contacts TP1 close to commence a new card feed cycle.

It should be observed that whenever during the operation of the machine any of the accumulators A, B or C stand at zero, after the entry period of any transfer cycle before cycle 8, there will be an entry of 99 plus a carry of 1 to effect a complete revolution in both accumulator orders so that the accumulator will in effect remain at 70 zero. To illustrate this, assume that there is no entry made in accumulator A from a card while there may be entries made in accumulators B and C. Accordingly, at the end of the card feed cycle relay F will be energized and CR5 will have 75 shifted lever 133 to position 2 resulting in the

energization of relay D, so that contact D2 is closed, and when CR3 close nearer the end of the cycle carry magnet 110 is also energized.

At the beginning of the first transfer cycle (cycle 2) therefore, relays D, F and magnet 110 are energized and emitter 1 will cause the amount 99 to be entered in accumulator A and later the extra or fugitive 1 is entered by the carry mechanism leaving the accumulator A at zero. This same sequence follows for the subsequent transfer 10 cycles so that, when any of the accumulators A, B or C stands at zero, it in effect does not have its setting changed.

The exact entries are tabulated below for the example of a multiplier of 990012 where 99 is 15 entered in accumulator A, 00 in accumulator B, and 12 in accumulator C.

Table IV

	ACC. A	ACC. B	ACC. C	20
1 Enter M.P.	99	00	12	
2 Transfer	50	99 1 Fug.	93 1 Fug.	25
3 Transfer	49	00	06	
4 do	75	99 1 Fug.	96 1 Fug.	30
5 do	24	00	03	
6 do	87	99 1 Fug.	98 1 Fug.	35
7 do	12	00	01	
8 do	93	99 1 Fug.	99 1 Fug.	40

Recapitulation

The operation of the mechanism will now be 45 briefly reviewed with particular reference to the problem of Fig. 11 to point out the sequence of operations. During the first cycle, as the card passes the brushes UB, the multiplier factor is sensed and entered into the accumulators A, B, and C and the multiplicand factor is entered into the accumulator MC. Toward the end of this cycle, the stepping relay is advanced so that relay 50 D may connect the MC, A, B, and C accumulators for entering under control of the readout devices. Near the end of the first cycle, the tens orders of the accumulators A, B, and C are sensed to determine whether the digits in these orders are even or odd. In connection with accumulator A, digit 5 is found to be odd and accordingly the magnet K for this order is energized. The magnets K for accumulators B and C remain deenergized. At the same time, the units orders are also sensed and the digits in all three are found to be odd, thereby causing energization of the relay magnets 1T, 2T, and 3T so that the readout device of accumulator MC is connected to transfer the amount 1580 to each of the accumulators #1, #2, and #3. Near the end of the transfer cycle, the brush of the stepping relay is again advanced and 55 the units and tens orders of the multiplier accumulators are tested. An even number is found in the tens order of the A accumulator so that its magnet K is not disturbed. The tens orders of the B and C accumulators are found to be odd and, 60 65 70 75 75

consequently, their relay magnets **K** are energized. The units order of the **C** accumulator contains the even digit "4" so that for this accumulator the carry magnet **110** is energized to enter 5 the additional unit during the next following cycle and the transfer magnet **3T** thereof is not energized.

This successive testing and entering goes on for 10 five more cycles, at the end of which time the entries in the **A**, **B**, and **C** accumulators will have been decreased to zero and the stepping relay will be in position to energize the gathering magnet **1G** so that the amount in **ACC#2** may be transferred to **ACC#3** and after this, upon further 15 advance of the stepping relay, the gathering magnet **2G** is energized to complete the gathering of the sub-products and finally, energization of the magnet **P** will bring the printing mechanism into operation and will complete the connections from 20 the readout devices of **ACC#3** to the printing magnets **58** and the accumulators will be reset in preparation for the entry of further factors from the next following card.

The machine has been disclosed for purposes of 25 illustration as containing three accumulators **A**, **B**, and **C** for the multiplier and three accumulators **#1**, **#2**, and **#3** to separately compute the sub-products. It is, of course, apparent that with a larger multiplier, additional accumulators may 30 be provided to take further pairs of multiplier digits and a further sub-product accumulator may be added for each additional pair of multiplier digits. The multiplier accumulators have been shown as comprising two orders each. If 35 smaller numbers, for example, numbers containing three places in the multiplier, are handled, the machine could be constructed with single-place multiplier accumulators, each of which will receive a single digit. In such case, the number of 40 doubling cycles will be reduced to three as a maximum and the three additional doubling cycles required where two-place multipliers are utilized could be eliminated.

While there has been shown and described and 45 pointed out the fundamental novel features of the invention as applied to several modifications, it will be understood that various omissions and substitutions and changes in the form and details of the device illustrated and in its operation may 50 be made by those skilled in the art without departing from the spirit of the invention. It is the intention therefore to be limited only as indicated by the scope of the following claims.

What is claimed is as follows:

55 1. In a multiplying machine, a pair of accumulators, means for entering an amount in each, means for ascertaining whether the amount in one of said accumulators is an odd number, a third accumulator, means for transferring the 60 amount in the second of said pair of accumulators to said third accumulator, and means controlled by said ascertaining means for effecting an operation of said transferring means when the number in said first accumulator is odd.

65 2. In a multiplying machine, a multiplicand accumulator, a multiplier accumulator, a readout device for each means for entering a factor in each, means including the readout device of the multiplicand accumulator for doubling the 70 amount in said multiplicand accumulator, means for effecting repeated operation of said doubling means, means operative for each doubling operation and including the readout device of the multiplier accumulator for reducing the amount 75 standing in the multiplier accumulator to half

the amount, if the amount is even, or to half the next lower even amount, if the amount is odd, means operative after each doubling operation for ascertaining whether the amount then standing on the multiplier accumulator is odd or even, a third accumulator, and means controlled by said ascertaining means for causing the amount standing in the multiplicand accumulator to be transferred to said accumulator whenever the said amount in the multiplier accumulator is an 10 odd number.

3. In a machine of the class described, a multiplicand accumulator, means for entering a multiplicand amount therein, a plurality of multiplier accumulators, means for entering a multiplier amount in each, a plurality of product accumulators, one for each multiplier accumulator, means for testing said multiplier accumulators to ascertain whether the amounts entered are even or odd numbers, and means controlled by said testing means for causing the multiplicand amount to be transferred to each of the product accumulators whose corresponding multiplier accumulator contains an odd number.

4. In a multiplying machine, an accumulator, means for entering amounts therein, the first amount being representative of a multiplicand, settable means controlled by the accumulator to represent the amount standing therein, means including said settable means, for controlling said entering means to cause the accumulator to control the settable means to represent, in succession and in ascending order, the terms of the geometrical progression whose ratio is 2 and whose first term is the said multiplicand amount, a second accumulator, means for entering amounts therein, the first amount being representative of a multiplier, settable means controlled by the second accumulator to represent the amount standing therein, means including said last settable means for controlling said last named entering means to cause the second accumulator to control its settable means to represent in succession and in descending order the terms of the geometrical progression having the same ratio as the 45 said ascending progression, whose first term is the said multiplier amount, each term of the descending progression being represented on its settable means concurrently with the representation of the corresponding term of the ascending progression on its settable means, a third accumulator, means for transferring the amounts standing on the settable means of the first named accumulator to said third accumulator, means for ascertaining for each term of the descending progression if the term is exactly divisible by the ratio 2 and means controlled by said ascertaining means when the term is not exactly divisible by 2 for causing said transferring means to transfer the corresponding term of the ascending progression from the first named settable means to said third accumulator.

5. In a multiplying machine, a pair of entry receiving devices, means for entering an amount 65 in each, means for ascertaining whether the amount in one of said devices is exactly divisible by 2, a third entry receiving device, means for controlling the operation of said third entry receiving device in accordance with the amount standing in the second of said pair of entry receiving devices, and means controlled by said ascertaining means for effecting an operation of said controlling means when the amount in said first entry receiving device is not exactly divisible by 2.

6. In a machine of the class described, an accumulator having a pair of denominational order elements, entering means therefor, means for causing said entering means to enter a number 5 into said elements, a device for each element, positioned thereby to represent any digit standing the related element, a second device, one for each element, positioned thereby to represent any odd digit standing in the related element, readout 10 means including an emitter for causing each of said first named devices to control their related denominational entering means to enter the 9's complement of half the digit standing therein if the digit is even and the 9's complement of the 15 next lower even digit if the digit standing therein is odd, means for normally entering an "elusive one" into the lower order accumulator element, means controlled by the second device of the higher order element, when an odd digit is represented thereon for causing part of said readout 20 means to control the entering means of the lower order element in accordance with the unit digit of the summation of the 9's complement of half the digit standing in the lower order increased 25 by five if the digit is even and in accordance with the units digits of the summation of the 9's complement of half the next lower digit, increased by five if the digit is odd, and means controlled by the second device of the lower order element, 30 when the digit represented thereon is odd for suppressing the entry of said "elusive one."

7. In a multiplying machine, an amount manifesting device, means for entering a multiplicand amount therein, means for operating said device 35 subsequent to the entry of said multiplicand amount to manifest in succession amounts representing each of the terms of a geometrical progression having a ratio of 2 of which progression said multiplicand amount constitutes the first and 40 lowest term, a second amount manifesting device, means for entering a multiplier amount therein, means for operating said device to manifest in succession amounts representing each of the terms of a geometrical progression having said 45 ratio of 2, of which progression said multiplier amount constitutes the first and highest term, the corresponding terms in each progression being concurrently manifested, an accumulator, means for ascertaining whether the terms of said second 50 progression are exactly divisible by said ratio, and means controlled thereby, for causing the ac-

cumulator to be controlled in accordance with the terms in the first progression whose corresponding terms in the second progression are not exactly divisible by the ratio.

8. In a multiplying machine an accumulator, 5 means for entering amounts therein, the first amount being representative of a multiplicand, settable means controlled by the accumulator to represent the amount standing therein, means including said settable means, for controlling said 10 entering means to cause the accumulator to control the settable means to represent, in succession and in ascending order, the terms of a geometrical progression whose ratio is 2 and whose first term is the said multiplicand amount, a plurality of 15 multiplier accumulators, means for entering amounts in each, the first amount in each being representative of a multiplier, settable means for each multiplier accumulator controlled thereby 20 to represent the amount standing therein, means related to each multiplier accumulator and including its related settable means, for controlling its entering means to cause each of said accumulators to control its settable means to represent 25 in succession and in descending order the terms of the geometrical progression having the same ratio as the said ascending progression, whose first term is the multiplier amount, the terms of the descending progression in the multiplier accumulators being represented on their settable 30 means concurrently with the representation of the corresponding term of the ascending progression on its settable means, a plurality of product accumulators, one for each multiplier accumula- 35 tor, means for transferring the amounts standing on the settable means of the multiplicand accumulator to each of said product accumulators, separate means for each multiplier accumulator for ascertaining for each term of the related 40 descending progression if the term is exactly divisible by the ratio of the progression, and means controlled by each ascertaining means when the term in the corresponding accumulator is not exactly divisible by said ratio for causing said transferring means to transfer the corresponding term of the ascending progression from the settable means of the multiplicand accumulator to the related product accumulator. 45
